UNITED STATES PATENT OFFICE.

HERBERT B. WALLING, OF SALT LAKE CITY, UTAH.

SCREENING AND CONCENTRATING DEVICE.

1,391,026.

Specification of Letters Patent. Patented Sept. 20, 1921.

Application filed June 2, 1920. Serial No. 385,912.

To all whom it may concern:

Be it known that I, HERBERT B. WALLING, a citizen of the United States, residing at Salt Lake City, in the county of Salt Lake 5 and State of Utah, have invented certain new and useful Improvements in a Screening and Concentrating Device, of which the following is a specification.

This invention relates to a screening and 10 concentrating device and it is an object of the invention to provide a novel and improved device of this general character especially designed and adapted to be employed for concentrating fine gold from ore bearing 15 gravel, sand or mine tailings.

A further object of the invention is to generally improve upon devices of this character by providing a device which will be substantially simple, durable and inexpensive in construction, one which is efficient 20 and reliable in operation, and well adapted to the purposes for which it is designed.

The invention consists in the details of construction and in the combination and arrangement of the several parts of my improved screening and concentrating device whereby certain important advantages are obtained and the device is rendered more 25 convenient and advantageous for use than those of like character now on the market, all as will be hereinafter more fully set forth.

With these and numerous other objects in view, the invention resides in certain novel 30 features of construction, and the combination and arrangement of parts as will be more fully described and especially pointed out in the appended claims.

In the accompanying drawings:

Figure 1 is a side elevation of the device.

Fig. 2 is a top plan view of the device.

Fig. 3 is a section taken on the line 3—3 of Fig. 2.

Fig. 4 is a fragmentary side elevation of 45 the device showing portions thereof in section.

Fig. 5 is a fragmentary top plan view of the lower portion of the device.

Fig. 6 is a section taken on the line 6—6 50 of Fig. 5.

Fig. 7 is a longitudinal section taken through the discharge valve used in connection with my invention.

Fig. 8 is a perspective view of the screen 55 cleaner.

Fig. 9 is a fragmentary side elevation of a

portion of the screen showing the adjusting means for the screen cleaner, and

Fig. 10 is a fragmentary side elevation of a portion of the lower portion of the device 60 showing a modified form of operating means.

In the preferred embodiment of my invention S indicates the screen generally and T the tank which is situated below the screen 65 S. It will be noted that the screen is inclined while the tank is substantially horizontal and that they are connected by means of the extension indicated by the letter E.

The screen S consists of a plurality of sections as shown in Fig. 2 of the drawing and, of course, the ore enters the screen at the mouth 1 by means of water and flows over these various sections so that the finer ore, looking at Fig. 2, will pass through the first 70 section and a thicker portion of the ore through the second section et cetera. There may be as many of these sections as may be desired.

By referring to Fig. 3 of the drawing it 80 will be seen that cleats 2 are disposed upon the sides of the screen for supporting the angle irons 3 which in turn support the floor 4. This floor 4 is provided with a plurality of rectangular openings as may be seen in 85

Fig. 2 of the drawing and I have provided the inverted V-shaped angle irons 5 which are disposed along the longitudinal edges of these openings and are held in place by means of the clips 6 which are in turn connected to the floor 4 by the bolt and nut indicated by the numeral 7. Looking at Fig. 9 it will be seen that the angle irons 3 are provided with the vertical rectangular openings 8 which have the ears extending outwardly therefrom at their top and bottom as indicated by the numerals 9. These ears 9 are provided with threaded apertures for receiving the set screws 10 which carry the box 11 for receiving the rod 12. Pivoted 90

upon this rod 12 are the screen cleaning devices as shown to advantage in Fig. 8 of the drawing. Each of these screen cleaning devices 8 tapers toward one end and is provided with the plate 12' having the 95 smaller blocks 13 at one end and the larger blocks 14 at its other end. These smaller blocks 13 are provided with the perforations 15 which also extend through the plate 12' for receiving the rod 12. A longitudinally extending slot 16 is provided in the plate 12' adjacent the larger end for re-

ceiving the crank 17 of the crank rod 18. This crank rod 18 is journaled in the side of the screen and as shown in Fig. 1 is provided with the end crank 19 which is connected with the reciprocating rod 20 which may be operated by any suitable means. From the above it will be seen that the larger end of the plate 12' will move up and down so as to let a portion of the ore pass through the rectangular openings provided in the plate 4 and that the pivot point of the plate 12' may be adjusted as desired for regulating the fineness of the ore which it is desired to pass through the various openings.

The tank T which is disposed immediately below the screening device consists of a plurality of compartments which should be immediately disposed below each compartment 20 of the screening device and should also be of the same dimensions as to length and breadth but of course the depth thereof will be considerably greater than the screen. In each compartment of the tank T there is a supplementary compartment indicated by the numeral 20 and is shown to advantage in Figs. 5 and 6 of the drawing. This compartment 20 is set off to itself by means of the partition 21. In the partition 21 there is provided an opening 22 adjacent the bottom thereof so as to place the compartment 20 into communication with the main compartment 23.

The compartments 23 form hoppers in the tank and are provided with the spiral screws 24, the blade of the spiral being cut away so as to form flattened portions 25 as shown in Fig. 4 of the drawing, these flattened portions being immediately above the axis 26 of the screws. A full spiral screw 27 is also provided within the hopper and disposed between and below the screws 24. As is shown in Fig. 4 of the drawing the hopper is formed with the V-shaped portion 28 having the arcuate extensions 29 which are concentric with the periphery of the blade of the screws 24. The full spiral 27 is disposed approximately in the apex of the V-shaped portion 28 and is adapted to deliver the ore through the opening 22 into the supplementary compartment 20.

In order to operate the fragmentary spiral screws 24 I have provided the cranks 30 upon the ends of the axles thereof which cranks 30 are connected to the reciprocating rod 31 thus giving an oscillatory movement to the fragmentary spiral screws 24. This reciprocating rod 31 may be operated by any suitable means. Upon the axles of the full spirals 27 I have provided the gear wheels 32 which are in mesh with the worm gear 33 on the rod 34. This rod 34 may be rotated by any suitable means.

In Fig. 10 I have shown a modified form 65 of operating means which is to be used when

it is desired to oscillate the full spiral screw 27 instead of rotating same. This modification consists of the cranks 30 and reciprocating rod 31 and also the gear wheel 32 but it will be noted that this gear 32 is provided with the squared knob 35 so that the arm 36 which is pivoted to a portion of the reciprocating rod 31 and has the forked portion 37, may embrace this knob 35 and thus the reciprocation of the rod 31 will impart oscillatory movement to the full spiral screw 27. It should be understood that the forked portion has a sufficiently large slot so as to allow for the movement of the rod 31.

In Figs. 5, 6 and 7 of the drawing I have illustrated a discharge valve which is to be used in the supplementary compartment 20. This discharge valve consists of the casing 40 having the spout 41 intermediate its ends and this casing is provided with the openings 42 which are disposed diametrically opposite the spout 41. Within the casing is disposed the valve member 43 having the knob 44 at one end and it will be noted that the valve member 43 is hollow and is open at the bottom so that the liquid may pass therethrough. An elongated slot 44 is provided in the body portion so that the valve portion 43 may be rotated so as to take this slot 44 in alinement with the spout 41. It will also be seen that this valve member is capable of vertical movement thus allowing more or less liquid to flow through the opening 42 into the casing. The pulp as it is forced into the compartment 20 being too thick to work in the discharge valve it is necessary to keep this compartment 20 full of water thus maintaining a pressure which will sufficiently lessen the density of the pulp so that it will rush through the discharge valve. The discharge valve can be adjusted so as to feed from the bottom and save the necessity of shoveling out the bottom of this compartment 20 and I have found by experience that this siphon will work very efficiently.

From the foregoing description, it is thought that the screening and concentrating device constructed in accordance with my invention is of an extremely simple and 115 comparatively inexpensive nature and is practically well adapted for use by reason of the convenience and facility with which it may be assembled and adjusted, and it will also be obvious that my invention is susceptible of some change and modification without material departure from the principle and spirit and for this reason I do not wish to be understood as limiting myself to the precise arrangement and formation of the several parts herein shown in carrying out my invention in practice.

Having thus described my invention what I claim as new is:—

1. A screening device of the class de- 130

scribed comprising a floor having a plurality of openings therein, agitating plates pivotally carried below said openings, means for oscillating said plates, and means for 5 vertically adjusting the pivot point of said plates.

2. A screening device of the class described comprising a floor having a plurality of openings, agitating plates formed 10 so as to taper toward one end pivotally carried at their smaller ends, means for vertically adjusting the pivot of said plates, a longitudinal slot provided in each plate, crank shafts provided in said screening device 15 vice so that the cranks thereof will be disposed in said slots, means for oscillating

said crank shafts whereby the larger end of said plate will be raised and lowered.

3. A screening device of the class described comprising a floor having a plurality of rectangular openings, agitating plates situated below said openings, a rod 20 passing through one end of said plates, means for adjusting said rod vertically, and means provided for oscillating said plates 25 upon said rod.

In testimony whereof I affix my signature in presence of two witnesses.

HERBERT B. WALLING.
